FIG. 1 is a side elevation of a sail boat, showing my new design;

FIG. 2 is a top plan view with the sail omitted and the mast broken away for convenience in illustration;

FIG. 3 is a fragmentary front elevation;

FIG. 4 is a fragmentary rear elevation;

FIG. 5 is a transverse section taken on the line 5—5 of FIG. 2; and

FIG. 6 is a longitudinal section taken on the line 6—6 of FIG. 2.

The dominant features of my invention reside in the portions shown in full lines.

I claim:

The ornamental design for a sail boat, as shown and described.
